NOZZLE LINING MACHINE

John M. Hothersall, Brooklyn, N. Y., assignor to
 American Can Company, New York, N. Y., a
 corporation of New Jersey

Application December 26, 1940, Serial No. 371,697

4 Claims. (CL 113—80)

The present invention relates to nozzle lining machines and the like and has particular reference to applying a gasket of compound lining material to the nozzles of can ends having curled flanges and to arranging the lined ends in a stack preparatory to drying the compound lining.

An object of the invention is the provision, in a flange curling machine for can ends having attached nozzles, of means wherein the nozzles are lined with a fluid compound gasket material and are simultaneously arranged in a stack ready for drying in a manner which permits of high speed production and which reduces extra handling of the can parts.

Another object of the invention is the provision of such a machine wherein the can ends are turned over during their passage through the machine so that they may be in one required position for the flange curling operation and in a required inverted position for the lining operation.

Another object is the provision of a machine of this character wherein can ends to be lined progress through the machine in a continuous procession, advancing in a step-by-step manner through various working stations which are combined to form a compact, efficient and high speed apparatus.

Numerous other objects and advantages of the invention will be apparent as it is better understood from the following description, which, taken in connection with the accompanying drawings, discloses a preferred embodiment thereof.

Referring to the drawings:

Fig. 1 is a top plan view of a machine embodying the instant invention, with parts broken away and parts removed;

Figs. 2 and 3 are fragmentary enlarged sectional details illustrating the nozzle portion of a can end and a portion of a lining die in different positions incident to applying a gasket of compound lining material to the nozzle;

Fig. 4 is a vertical longitudinal section taken substantially along the line 4—4 in Fig. 1, with parts broken away and with parts shown in elevation;

Fig. 5 is an enlarged vertical transverse section taken substantially along the line 5—5 in Fig. 1, with parts broken away;

Fig. 6 is a vertical section taken substantially along the line 6—6 in Fig. 5, with parts broken away;

Fig. 7 is a horizontal section taken substan-

tially along the line 7—7 in Fig. 6, with parts broken away;

Fig. 8 is a side elevation of a portion of the machine, the view showing the side opposite to that illustrated in Fig. 4, with parts broken away;

Fig. 9 is an enlarged vertical section taken substantially along the broken line 9—9 in Fig. 4, with parts broken away; and

Fig. 10 is an enlarged vertical section taken substantially along the line 10—10 in Fig. 4, with parts broken away.

As a preferred embodiment of the invention the drawings illustrate principal parts of a sheet metal can end flange curling machine which includes mechanism for inverting the can ends and for lining the nozzles and for arranging the lined can ends into a stack. Such a machine is adapted to operate on rectangular shaped, rounded corner can ends A of the character used in oil cans and the like which are fitted with dispensing spouts. The spouts are secured to nozzles B (see Figs. 2, 3, 5 and 6) the latter preferably being formed as an integral part of the can ends. These nozzles are formed with a flat seat C which is adapted to receive the spout and which is adapted to be provided with a gasket D to produce a hermetic joint between the spout and the nozzle seat.

In the machine, peripheral flanges E on the can ends A are first bent inwardly to form a curled edge or flange F which is subsequently utilized in securing the can end to a can body in a suitable seam to produce the finished container. For best results the can end A is preferably positioned with its nozzle extending upwardly as shown in Fig. 4, during this flange curling operation.

Application of the gasket D to the nozzle B is preferably effected when the can end is in an inverted position so that the nozzle extends down. Hence following the flange curling operation the can end A is inverted to bring the nozzle to the desired position and immediately following this a fluid compound lining material is applied to the nozzle seat C to form the gasket D. Just after this compound lining step the can end A is lifted vertically into a stack where it takes its place with the previously lined can ends ready for drying. When the lined can ends have been built-up into a stack of sufficient height, the entire stack may be manually removed to any suitable place of deposit for drying.

The can ends A upon entering the machine are advanced along a straight path of travel in a step-by-step or intermittent manner between

a pair of spaced and parallel guide rails 11 (Figs. 1, 4 and 10). The guide rails are secured to a pair of spaced and parallel runway bars 12 on which the can ends are supported. These runway bars extend longitudinally of the machine and are bolted to the top of a table 13 formed as an integral part of a frame 14 which constitutes the main frame of the machine.

Advancement of the can ends A along the runway bars 12 and the guide rails 11 is preferably effected by spring held dogs 16 which are carried at spaced intervals in a reciprocating feed bar 17. The feed bar is supported on the top of the table 13 and is disposed between the runway bars 12 in slideway grooves 18 formed in the bars. The runway bars thus serve as gibbs for the feed bar.

Reciprocation of the feed bar 17 through a forward or advancing stroke and backward through a return stroke is preferably brought about by a segment gear 21 which meshes with rack teeth 22 formed in the bottom of the feed bar. The rack teeth extend down below the feed bar and operate in a clearance groove 23 formed in the table 13 while the segment gear operates in a clearance slot 24 also formed in the table. The segment gear 21 is part of a lever 26 which is mounted on a pivot pin 27 carried in the main frame 14. This lever is actuated or oscillated in any suitable manner in time with the other moving parts of the machine.

On a forward stroke of the feed bar 17 a can end A is advanced along the runway bars 12 and is deposited on top of a lifter 31 disposed at a curling station K (Figs. 1, 4, 10). The bottom of the lifter is provided with a vertical stem 35 which is carried in a bearing 36 in the bottom of the boss 31. This stem extends down below its bearing and is raised and lowered in any suitable manner in time with the other moving parts of the machine. An elongated slot 38 in the lifter provides clearance for the feed bar 17.

When a can end A is received on the lifter 31 it is raised vertically by the lifter into a rotating curling head generally indicated by the numeral 41. This head is preferably enclosed in and supported by a hood 42 which is secured to an upright support web 43 formed integrally with the main frame 14. The head is continuously rotated in any suitable manner and is provided with a stationary chuck 45 and a plurality of curling rollers 46. The rollers rotate with the head. This is a usual curling head construction.

Thus when the can end A is lifted into the curling head 41 it is forced into engagement with the chuck 45 and it is thus held stationary. While the can end is so held, the curling rollers move in against its flange E and rotate around the can end. It is this rolling action that forms the curl or flange F.

During this can end flange curling operation the feed bar 17 moves back through a return stroke and brings an advanced feed dog 16 into position adjacent the lifter 31. Following the curling operation the lifter descends and returns the curled can end to its original position level with the runway bars 12. The feed bar thereupon moves through a forward stroke and the feed dog 16 engages against the can end and advances it one step along its path of travel. This advancement of the curled can end removes it from the lifter 31 and shifts it onto a pair of continuing runway bars 51 which carry continuing guide rails 52. These runway bars are secured to the table 13. The can ends A are prevented from retrograde movement with the spring held

dogs on the reciprocating feed bar 17, by means of friction exerted against the ends in the runway as they are being intermittently advanced by the dogs between the guide rails 11. Spring held guide plates or can end retaining bars are employed for this purpose adjacent the runway, for example as shown at 155, 156 in the patent to Butler 2,085,001, issued June 29, 1937, for a Flange curling machine. Since such spring held guide elements are well known in the art and are not specifically claimed in the instant application, they have not been illustrated in detail.

On succeeding forward strokes of the feed bar 17 the curled can end is advanced through a plurality of idle stations and is then introduced into a turn-over or inverting station L (Figs. 1, 4 and 9). At this station the feed bar inserts the can end A into a rotatable turn-over wheel or cylinder 55. The cylinder is carried in a bearing 56 formed in an end wall 57 of a fluid lining compound tank 58. The tank is formed as a part of a bracket 59 which is bolted to an end wall of the machine frame 14.

The inserted can end A is located in an elongated opening 61 of the turn-over cylinder and its longitudinal curled flanges F are disposed in a pair of spaced and parallel holding grooves 62, 63. Groove 62 is formed in the cylinder wall adjacent the opening 61 and is located in the middle of the cylinder. Groove 63 is formed in a rectangular spring barrel 65 disposed in a recess 66 formed in the cylinder wall diametrically opposite the groove 62. The barrel is backed up by a compression spring 67 which is held in place by a screw 68. The spring presses the barrel against a can end received in the turn-over cylinder and thus frictionally holds it in place.

When a can end is received in the turn-over cylinder 55 and after the feed bar 17 has moved rearwardly on a return stroke, the cylinder is rotated through one-half a revolution and the can end retained therein is thus turned over into an inverted position with its nozzle extending downwardly as shown in Fig. 3. Rotation of the cylinder through this half revolution is brought about by gear teeth 71 which are formed on the entrance end of the cylinder. The gear teeth mesh with a vertical rack 72 which slides in a bearing 73 formed on the tank 58.

The lower end of the rack 72 is pivotally connected to the outer end of a cam arm 75 which is mounted on a pivot pin 76 carried in a boss 77 formed on the bracket 59. Intermediate its ends, the arm carries a cam roller 78 which operates in a cam groove 79 formed in the inner face of a rotary cam 81. The cam is mounted on a cam shaft 82 which is journaled in a long bearing 83 formed in the bracket 59. The shaft is rotated by a gear 84 which is mounted on one end thereof. This gear meshes with a pinion 85 mounted on one end of a driving shaft 86 journaled in a long bearing 87 formed in the bracket 59. The opposite end of the driving shaft carries a sprocket 88 which is driven by a chain 89. The chain may be driven in any suitable manner in time with the other moving parts of the machine.

Since the center of the turn-over cylinder 55 is in alignment with the feed line or the path of travel of the can ends moving through the machine, a can end after being turned over is still in alignment with the feed line. Hence upon the next forward stroke of the feed bar 17, it again enters the opening 61 in the cylinder and pushes the inverted can end out and advances it into

the next station. This is a nozzle lining and stacking station M (Figs. 1, 4, 5, 6 and 7).

At the nozzle lining and stacking station M the inverted can end A is received in a pair of oppositely disposed holding fingers 92 having long faces containing holding grooves 93 in which the longitudinal curled flanges F of the received can end engage. Fingers 92 are mounted on pivot pins 94 carried in lugs 95 formed on the bottom ends of a pair of stacking slides 96. Each slide is located on a side of the received can end A. These slides are disposed in slideways 97 formed in slide brackets 98 secured to a base plate 99 which extends across the top of the compound tank 58 and is bolted thereto.

The upper ends of the holding fingers 92 are backed up by spring barrels 101 which are disposed in bores 102 formed in the slides 96. These spring barrels force the fingers inwardly against the can end to hold it in place. The lower ends of the fingers are formed with stop lugs 103 which engage against an inclined surface 104 on each slide and thus limit the inward movement of the fingers when no can end is held by them.

The inverted can end A thus held in place by the holding fingers 92 is located directly above the compound lining tank 58 in an opening 105 in the base plate 99 and below and in vertical alignment with a lined can end magazine 107 which is defined by a pair of right angle vertical stack retaining rails 108. These rails are formed as a part of the stacking slide brackets 98. It is while the can end is in this position that its inverted nozzle B receives the compound gasket D hereinbefore mentioned.

Application of the gasket D is effected by a hollow conical die head 111 which is disposed in vertical alignment with and below the inverted nozzle B of the held can end. The die head is formed with a flat lining seat 112 and this head is normally disposed in a bath of fluid lining compound 113 contained in the tank 58.

The die head 111 is preferably formed on an L-shaped arm 115 which extends upwardly out of the tank and is secured to a bracket arm 116 which projects inwardly from a vertical slide 117. This slide is carried in a slideway 118 formed in a slide bracket 119 which is integral with a side wall of the tank 58. The slide is connected by a link 121 to one end of a lever 122 mounted on a pivot pin 123 secured in a lug 124 which extends up from the side wall of the tank. The opposite end of the lever is connected by a link 126 carried on a pivot pin 127 secured in the driving sprocket 88 in an off-center position. The pin 127 thus serves as a crank.

Hence as the sprocket 88 rotates, it rocks the link 126 and lever 122 and thus moves the slide 117 through an upward or operating stroke and thence downwardly through a return stroke. On the upward stroke of the slide, it lifts the die head 111 out of the compound lining material in the tank 58 and carries it up toward the positioned nozzle B. The die head thus carries up with it on its seat 112 (Fig. 2) a film of material which is a predetermined quantity of the compound.

Any compound which is on the conical portion of the die head drains off onto the seat 112. To facilitate this drainage a plurality of holes 128 are formed in the die head and these holes permit the compound to flow into a communicating passage-way 129 formed in the L-shaped arm

115. This passage-way is open at its bottom end and thereby permits the compound to return to the tank. In practice substantially only the seat 112 of the die head carries the compound up out of the tank.

At the top of the upward stroke of the die head 111 its compound laden seat 112 engages with the flat seat C of the can end nozzle B and the compound carried by the die head is thereby transferred to the nozzle seat. It is this applied compound that constitutes the gasket D.

After the compound is applied to the nozzle B the die head 111 returns to its lowered original position within the tank 58 beneath the level of the fluid lining compound therein, in readiness for lining the next can end in the procession. During this descent of the die head the gasket lined can end A is lifted vertically into the magazine 107. This lifting of the can end is brought about by the stacking slides 96 hereinbefore mentioned. For effecting proper slide movement each stacking slide is connected by a link 131 to the outer end of an operating arm 132.

There are two of these operating arms 132 (Figs. 1 and 5) and they are secured to a cross shaft 133 carried in bearings 134 formed on the slide brackets 98. One of the arms is formed with a depending lever arm 136 (see also Fig. 4) which at its lower end carries a cam roller 137. The cam roller operates in a cam groove 138 formed in the outer face of the gear 84.

Hence as the gear 84 rotates it rocks the operating arms 132 at the proper time and thus shifts the stacking slides 96 in unison through an upward or stacking stroke and thence downward on a return stroke to their original position. On the upward stroke of the slides, the holding fingers 92 are lifted and the lined can end A held by them. The slides carry the can end up past a plurality of yieldable stack supporting fingers 141 which snap back after allowing the can ends to pass and then hold them in the magazine 107.

There are four of the stack supporting fingers 141 two being located at the two sides of each oppositely disposed holding finger 92. Each of the supporting fingers is mounted on a pivot pin 142 (Figs. 5 and 7) which is secured in a lug 143 formed on the base plate 99. The upper end of the fingers 92 extend into the bottom of the magazine and normally project out into the magazine where they engage under and support the can ends as they are being stacked in the magazine.

Adjacent its pivot pin 142 each supporting finger 141 is formed with an outwardly projecting horizontal lug 145 which extends into a recess 146 in the base plate and engages against the base plate. This portion of the base plate thus serves as a stop to hold the supporting fingers 141 in proper position. The lugs are held against the base plate by flat springs 147 each having one end engaging the lug of its adjacent finger and having its opposite end secured to the base plate. It is these springs that yield and permit the supporting fingers to shift inwardly as a can end A passes by under the lifting action of the stacking slides 96 and holding fingers 92 thereon carrying the can end up into the magazine.

The rising stacking slides 96 thus lift the newly lined can end A just above the top edges of the supporting fingers 141 and the latter snap back to a holding position under the can end. The stacking slides then move down on their return stroke and bring the holding fingers 92 back into alignment with the feed line of the can ends and

they will then be in position for the next advancing can end. As the stacking slides move down, the can end A comes into engagement with the top edges of the supporting fingers 141 and further downward travel is thereby arrested. This arresting of the can end movement strips it out of the holding fingers 92 against the resistance of their spring barrels 101 and thus the can end is left in the magazine resting on the supporting fingers.

In this manner each can end A after its nozzle B receives a gasket D, is lifted into position in the magazine 107 and this action builds up a vertical stack of such can ends. Each time a newly lined can end is lifted, it engages the bottom end in the stack and raises the entire stack, the newly received and lined can end thus taking its place at the bottom of the stack. The stack is held in stack form by the retaining rails 108 and when sufficient ends have been brought into the magazine, the stack may be manually removed to any suitable place of deposit for drying of the gaskets D.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A can end nozzle lining machine, comprising in combination a tank containing a bath of fluid compound lining material, a vertically movable die head disposed in the lining material in said tank, holding instrumentalities disposed above said tank for holding in a predetermined position an inverted can end having a nozzle with the nozzle in vertical alignment with said die head, a magazine disposed above and in vertical alignment with said holding instrumentalities, means for elevating said die head into direct engagement with the under surface of the can end nozzle to carry up a quantity of the lining material from the tank and to deposit it in the nozzle to provide a gasket of predetermined configuration therein, and devices operating in time with the movement of said die head for elevating the can end vertically from said holding instrumentalities after said can end has received its gasket, said elevating devices depositing the lined can end in said magazine.

2. A can end nozzle lining machine, comprising

ing in combination a vertical magazine for retaining lined can ends in stacked position, holding instrumentalities below said magazine and in vertical alignment therewith for holding an unlined can end having an attached nozzle so that it is in a predetermined inverted position relative to said magazine, a vertically movable die head disposed below the held unlined can end for applying a gasket of fluid compound lining material to said nozzle, and devices operating in time with said die head for lifting the can end vertically into the magazine after it has received its gasket.

3. A can end nozzle lining machine, comprising in combination a vertical magazine for retaining lined can ends in stacked position, a vertically movable slide device located adjacent said magazine, a pair of oppositely disposed yieldable fingers carried in said slide device for holding an unlined can end having a nozzle so that it is in predetermined position and is in alignment with said magazine, a vertically movable die head disposed in a bath of fluid compound lining material located below the positioned unlined can end for carrying up a predetermined quantity of the lining material and for depositing it in the nozzle of the can end; means operating in time with said die head for shifting said slide devices to rise the newly lined can end into the magazine just after it has received its gasket, and yieldable supporting fingers in said magazine for stripping the raised can end from the holding fingers and for supporting it at the bottom of a stack of previously stacked lined can ends in the magazine.

4. A can end nozzle lining machine comprising feeding devices for advancing can ends having nozzles thereon with the nozzles disposed in upright feeding position, a turn-over device disposed in the path of the can ends for receiving a said can end in its upright position as advanced by said feeding devices and for turning the can end over into an inverted position, holding instrumentalities located adjacent said turn-over device for receiving and holding the inverted can end, a vertically movable die head disposed below the held inverted can end for applying a gasket of fluid compound lining material to said nozzle, a magazine located above and in vertical alignment with said die head for retaining lined can ends in stacked position, and devices operating in time with said die head and said turn-over device for lifting the can end vertically from said holding instrumentalities into the magazine after it has received its gasket lining.

JOHN M. HOTHERSALL.
